UNITED STATES PATENT OFFICE

WILLIE L. HOLBROOKS, OF HOUSTON, TEXAS

DREDGE BOAT CONSTRUCTION

Application filed May 2, 1932. Serial No. 608,833.

This invention relates to a dredge boat construction and has more particular relation to novel means for mounting the suction hose employed.

5 An object of the invention is to provide, in a dredge boat, a novel type of hose box for mounting the suction hose, or suction pipe, employed.

As at present constructed the ordinary 10 dredge boat has a forwardly extended ladder, hinged thereto, for supporting and controlling the cutters or diggers which disintegrate the shell or aggregate to be recovered, and supported by said ladder there is a 15 suction hose, or pipe, by means of which the material to be recovered is delivered to the barge or other vehicle provided for the transportation of the same. It is an object 20 of this invention to provide, in a dredge boat, novel means for anchoring said suction hose to the dredge in such manner that the hose will be protected and at the same time will have the required freedom of movement.

With the above and other objects in view 25 this invention has particular relation to certain novel features of construction, arrangement of parts and use an example of which is given in this specification and illustrated in the accompanying drawing, wherein:

30 Figure 1 shows a fragmentary longitudinal sectional view of a dredge boat illustrating the improvements.

Figure 2 shows a longitudinal sectional view of the hose box, shown installed, and

35 Figure 3 shows a front end view of said box.

Referring now more particularly to the drawing wherein like numerals of reference 40 designate the same parts in each of the figures the numeral 1 designates the dredge boat as a whole, which may be of any selected construction.

Pivottally mounted on the bow of the boat 45 1 is the forwardly extending ladder 2 whose free end supports the cutting knives which dig up the material to be recovered. Beneath and supported by said ladder there is a suction pipe 3 through which the loose material, dug up by said knives, is conveyed,

by suction, and discharged onto a barge or other vehicle provided therefor.

Attached to the bow of the barge there is an inwardly, or aftwardly, extended hose box 4 which is tapered, or gradually contracted aftwardly and whose rear end is open. This box is rectangular in cross sectional contour and its forward, or large, end is fitted through the forward wall 5 of the dredge boat 1. Surrounding the forward 55 end of said box and secured thereto on opposite sides of the wall 5 are the angle iron collars 6, 6 whose outstanding flanges are clamped closely against said wall by the bolts 7 which pass through said flanges and 60 wall and which secure the box firmly in place.

The inner end of said box 4 has the end 65 plate 8 secured thereto and having a central opening 9 and the adjoining ends of adjacent sections of the pipe 3 are clamped to opposite sides of said plate 8, in alignment with said opening 9, by the clamp bolts 10. The suction pipe 3 extends through said box 4 and the section thereof, extending into the 70 box, may be formed of flexible hose 11 so that that portion of the suction pipe, carried by the ladder, may swing freely with said ladder. The box 4 is of such dimensions that the pipe 3 may swing freely therein as the 75 ladder is swung vertically or laterally while carrying on the work and without injury to the dredge boat or to the suction pipe.

The drawing and description disclose 80 what is now considered to be a preferred 85 formed of the invention by way of illustration only while the broad principle of the invention will be defined by the appended claims.

What I claim is:

1. The combination with a dredge boat 90 having a ladder pivoted thereto and a suction pipe which is supported by said ladder; an inwardly extending box through, and attached to, a wall of the boat through which said pipe extends and to the inner end of which said pipe is attached.

2. The combination with a dredge boat 95 having a ladder pivoted thereto and having 100

a suction pipe associated with said ladder; an inwardly extended box attached to the boat whose outer end is open, said pipe extending through said box and anchored to, and forming a fluid tight joint with, the inner end of said box.

3. The combination with a dredge boat having a ladder pivoted thereto and having a suction pipe associated with said ladder;

10 10 an inwardly extended box attached to the boat whose outer end is open, said pipe extending through said box and anchored to, and forming a fluid tight joint with, the inner end of said box, said pipe being formed flexible adjacent the outer end of the box.

15 15 4. The combination with a dredge boat having a ladder pivoted thereto and a suction pipe which is supported by said ladder; an inwardly extending box through, and attached to, a wall of the boat through which said pipe extends and to the inner end of which said pipe is attached, said box being flared outwardly.

20 20 5. In a dredge boat, a hose box adapted to be attached to and to extend through a wall of the boat and whose outer end is open, means for closing the inner end of the box, said closing means forming an anchor for a suction pipe.

25 25 6. In a dredge boat, a hose box adapted to be attached to and to extend through a wall of the boat and whose outer end is open, means for closing the inner end of the box, said closing means forming an anchor for a suction pipe, said box being outwardly flared.

30 In testimony whereof I have signed my name to this specification.

WILLIE L. HOLBROOKS.
